Application December 13, 1946, Serial No. 716,038

8 Claims. (Cl. 175—373)

1

This invention relates to delayed response electrical apparatus and resides more particularly in an improved form of delayed-action or interval timing circuit in which a grid-controlled gas-filled glow-discharge tube or grid-glow tube is related with other circuit elements in such fashion that firing of the tube is regulated by gradual charging of the grid and the interval during which the tube remains conducting upon firing is reduced to a minimum.

An object of this invention is to provide a delayed-action interval timing circuit apparatus dependent for its action upon a grid-glow tube in which tube life is greatly extended by reason of a very low ratio of active to inactive time of use of the tube.

Another object of this invention is to provide a delayed-action interval timing circuit apparatus dependent for its action upon a grid-glow tube in which increased dependability and consistency of response of the tube is obtained due to the comparatively brief periods during which the tube is loaded.

Another object of this invention is to provide a delayed-action interval timing circuit apparatus possessed of the advantages of constant readiness to perform without a "warm up delay" and of freedom from standby current requirements.

Another object of this invention is to provide a simplified delayed-action interval timing circuit apparatus adapted for operation with alternating current supply and capable of repetitive timing of successive intervals through a single interval determining instrumentality.

Delayed-action circuit apparatuses of various forms, depending upon the controlled functioning of thermionic or gaseous discharge devices have been extensively used. In the case of apparatus depending for operation upon thermionic devices, disadvantages are involved because of the necessity of maintaining standby conditions involving continuous supply of filament or heater current and because of the large expenditure of available tube life during idle conditions. A further disadvantage also is the waiting period for "warm up" that may be involved. The two element glow-discharge tube as heretofore employed has also suffered a disadvantage in that the quantity of energy available for actuation of a relay actuated thereby is limited to the charge prevailing in the capacitor at the moment of "striking" of the tube. If for any reason the relay does not react positively to the quantity of energy thus delivered, unreliable response is encountered. Such circuits are, therefore, depend-

2

ent upon undesirably delicate relays lacking in the ruggedness preferred for industrial equipment. The grid-glow or three element gaseous discharge tube has heretofore been little used for delayed-action circuits because its behavior in the circuits employed has been considered fickle and unreliable. Such unreliability has been attributed to shifting of tube characteristics as a result of the history of treatment to which the tube has been subjected. The grid-glow tube, however, is possessed of the advantage of being able to perform without standby demand and without "warm up" delay and may be controlled to continue supply of energy to a relay for any interval which may be required to cause its positive operation.

Through this invention consistent and dependable response is obtained in a delayed-action or interval timing circuit apparatus which is dependent upon a grid-glow tube for its operation by a novel circuit arrangement in which load is imposed upon the tube only so long as is required for positive relay operation. By reason of the very brief intervals during which load is imposed upon the grid-glow tube, shifting of tube characteristics is held well within limits such that practical consistency of operation is obtained. Furthermore, the total time of functioning required of the grid-glow tube for a large number of cycles is so short that the life of the tube in use is greatly extended.

This invention is herein described by reference to the accompanying drawing in which there is set forth by way of illustration and not of limitation one form in which the circuit of this invention may be embodied.

In the drawing the figure shows diagrammatically a circuit constructed in accordance with this invention applied to the regulation of the starting function of an alternating current induction motor.

As depicted in the drawing the time delay apparatus of this invention depends for its operation upon a cold cathode grid-controlled gas-filled glow-discharge tube 1. The cathode of tube 1 constituting one of its main electrodes is connected by a lead 2, a resistor 3, normally closed switch contacts 4 and lead 5 with an adjustable tap 6 of an auto transformer 7. The anode of tube 1 constituting the other main electrode is connected by lead 8 and lead 9 with one end of the winding of a relay 10. The opposite end of the winding of the relay 10 is connected by lead 11 with terminal 12 of the auto transformer 7. In this manner a plate circuit is provided through

which current may be passed to the relay 10 for energizing the same whenever the tube 1 becomes conducting.

The grid 13 of tube 1 is arranged to be charged at a regulated rate through the action of half wave rectifier 14. Rectifier 14 is connected on one side by lead 15 and lead 11 with terminal 12 of the auto transformer 7 and on the opposite side through leads 16 and 17 with a capacitor 18. The capacitor 18 is connected on its opposite side through a lead 18 with resistor 3 and thence through switch contacts 4 and lead 5 with the tap 6 of transformer 7. In this way, with transformer 7 supplied with alternating current through leads 20 and 21, the capacitor 18 becomes charged through the action of the rectifier 14, and lead 17 connected thereto is rendered positive with respect to lead 19.

Connected to lead 17 as shown is a variable resistor 22 having a movable side tap which is connected in turn through switch contacts 23 and lead 24 with one side of a capacitor 25. Alternatively connected to lead 17 is a variable resistor 22' which is connected in turn through switch contacts 23' and lead 24 with the capacitor 25 as shown. The opposite side of capacitor 25 is connected through lead 26 with lead 19 and, consequently, with the cathode of tube 1. Lead 24 is connected by lead 27, resistor 28 and lead 29 with the grid 13 of tube 1. Thus when current is supplied to the auto transformer 7 and lead 11 becomes negative, current flows through the relatively high resistance of resistor 22 (or resistor 22' depending upon the position of switch contacts 23 and 23') at a limited rate with the result that capacitor 25 gradually becomes charged. The rate at which capacitor 25 becomes charged may be altered by adjustment of resistor 22 or resistor 22' as the case may be so that the time required for the grid 13 to reach a charge which will cause firing of tube 1 may be adjusted.

Having selected an adjustment for the resistor 22 and having applied current to the auto transformer 7 the grid 13 of tube 1 will at some predetermined interval after commencement of excitation of transformer 7 reach a potential at which the tube 1 fires thus admitting current to the winding of relay 10.

Upon excitation of the winding of relay 10 the movable member of contact 4 is shifted into engagement with stationary contact 4' which is connected through lead 30 with the grid lead 27. In this way the capacitor 25 is caused to discharge through the resistor 3 which reduces the charge on the grid 13 of tube 1, thus preparing the same for a succeeding timing function. At the same time normally open contacts 31 become closed and this establishes a circuit through leads 32 and 33 which causes the capacitor 18 to empty its charge through the resistor 3 likewise. At the same time normally closed contacts 4 open thus breaking the supply of current to the cathode of tube 1.

In order that the relay 10 remain excited when desired after a single timing interval a maintaining circuit is provided which extends from line 11 through relay coil 10, leads 9 and 8, and thence through resistor 35, switch 34, rectifier 36, normally open contacts 37 and lead 38 back to line 5. This maintaining circuit is subject to being controlled by the switch 34 which when closed completes the maintaining circuit described. With the switch 34 open, the relay 10 upon firing of tube 1, moves to the closed position which prepares the circuit for the starting of a new timing

cycle and then immediately drops to start a new timing interval. For each energization of the relay 10 the tube 1 remains excited for only a very brief period. Usually two or three current cycles are sufficient to cause the relay 10 to move. The life of tube 1 thus is greatly extended even though a large number of timing cycles is employed since even under conditions of repeated timing cycles the total active time of the tube 1 is extremely small.

The interval timing circuit above described may be employed for any purpose which requires a switching function automatically regulated to occur at pre-determined intervals. One such requirement is the successive reduction of the secondary resistance of a wound rotor induction motor during starting. The drawing shows the timing circuit of this invention thus applied. As shown in the drawing a motor 39 is connected through leads 40, 41 and 42 with a load contactor 43 which is connected in turn with power supply mains 44, 45 and 46. Control current for closing the contactor 43 is supplied from main 46 and from thence passes through normally closed stop switch 47, normally open start switch 48, lead 52 and overload control 49 to the coil of contactor 43 from which connection to supply main 45 is provided by lead 50. Upon closure of the starting switch 48 the contactor 43 closes and in so doing establishes a maintaining circuit through stop switch 47, lead 51, auxiliary contacts 53, lead 52', overload control 49 to the coil of contactor 43 thus causing the contactor 43 to remain closed until the stop switch 47 is opened.

Upon closure of start switch 48 or of maintaining contacts 53, current also becomes supplied to the transformer 7 by reason of lead 54 which joins with lead 21 and by reason of the connection of lead 20 to switch 55, which in turn is connected through lead 56, normally closed contacts 57, to be described in greater detail later, and lead 58 with main 45. As a result of the closure of contactor 43, assuming switch 55 is in closed position, a timing interval is initiated in the timing circuit, and at the same time the motor 39 becomes energized with a maximum of resistance in its secondary circuit.

At the end of the first timing interval, assuming switch 34 to be open, normally open contacts 59 become closed momentarily and in so doing establish a circuit extending from line 45 through lead 58, lead 60, lead 61 to the winding of contactor 62 and thence through leads 63, 64, 65 and the contacts 59 to the lead 66 and thence through lead 54 and maintaining contacts 53, lead 51 and stop switch 47 back to power line 46. The establishment of this circuit causes contactor 62 to close and to short out the resistances 67 in the secondary of motor 39.

Upon closure of contactor 62 a maintaining circuit for causing the same to be retained in closed position is established through auxiliary contacts 68 and lead 69. At the same time through mechanical interlock 62' contacts 23 are opened and contacts 23' closed.

Following the first momentary closure of relay 10, normally closed contacts 70 re-engage and upon such re-engagement a subsequent step circuit, prepared by the closure of the auxiliary contacts 68, becomes completed. This subsequent step circuit extends from contacts 68 through lead 65 and through the contacts 70 and leads 71 and 72 to the winding of interlock relay 73, the other end of which winding is joined with lead

60. Relay 13, therefore, immediately closes and upon closing maintains itself in closed position through the action of auxiliary contacts 14 connected by lead 15 with lead 64 as shown.

The closure of relay 13 through closure of its contacts 16 then sets up but does not complete an energizing circuit for a contactor 11. The circuit thus prepared extends through lead 18, the winding of contactor 11, lead 19, contacts 16, lead 80 to a pair of normally open contacts 81. The contacts 81 are joined in turn through a lead 82 with lead 66. By reason of this preparatory action upon occurrence of the second succeeding closure of relay 10 at the end of the second timing interval, contactor 11 closes and in so doing eliminates the remaining resistances 83 from the secondary of motor 39. It will be understood that the duration of the first timing interval will be determined by the adjustment of resistor 22 while the duration of the following interval will be determined by the adjustment of resistor 22'. These two intervals may thus be independently varied within the limits of adjustment available.

Closure of contactor 11 also establishes its own maintaining circuit through maintaining contacts 84 and lead 85 causing it to remain closed after re-opening of relay 10. At the same time upon closure of contactor 11 the normally closed contacts 57 previously referred to are caused to open, thus interrupting power supply to the transformer 1 so as to terminate further repetition of timing intervals by the timing circuit. The motor 39 thus is brought up to operating speed through three successive stages of resistance in its secondary circuit and this sequence is performed automatically without intervention of the operator once the starting switch 48 is closed. In order to stop the motor the stop switch 47 is opened causing contactors 43, 62 and 11 to drop open closing contacts 57 and also de-energizing relay 13. The circuit is thus brought into condition for execution of a new starting sequence whenever start switch 48 is again closed.

If it is desired that the motor 39 be run at reduced speed switch 55 may be opened before closing of the starting switch 48. In this case the motor 39 will continue to run with maximum resistance in the secondary circuit. If it is desired that the motor run at an intermediate rate the switch 55 may be closed and the switch 34 also. Under such circumstances a single timing sequence only will occur and the motor 39 will be caused to run with the resistance 83 only in the secondary circuit. It will be understood that for normal starting, switch 55 is closed and switch 34 is allowed to remain open.

It will be observed that the tube 1 is subjected, in the operation of the circuit of this invention, to load carrying conditions only for so long as is required for the relay 10 to positively close, an action aided by the capacitor 86. Immediately on closing of relay 10 the opening of contacts 4 terminates passage of current through the tube 1. The actual period of loading of tube 1 need not be more than 2 or 3 current cycles and this interval is so short that no perceptible change in the characteristics of the tube results. The response on repetition of successive timing intervals, therefore, remains reasonably constant and reliable for a very large number of timing functions. The principle involved further obviously is not limited to but two successive timing intervals since the timing circuit will repeat as often as need be to meet the requirements of any control circuit dependent thereon.

I claim:

1. In an interval timing circuit a current source adapted to be controllably activated; a grid-glow tube having main electrodes and a grid; a charging circuit for said grid including a resistor and a grid charging capacitor; said capacitor being connected on one side to one of the main electrodes of said tube and to one side of said current source and connected on its other side through said resistor to the other side of said current source to said current source and to said grid for charging the same to a striking potential at a pre-determined interval after activation of said current source; and a relay connected through said main electrodes of said grid-glow tube to a source of actuating current, said relay including contacts interposed in the connections joining said relay with said actuating current source to interrupt the supply of actuating current for said relay and including contacts connected in discharging relationship to said capacitor to discharge said grid charging capacitor upon excitation of said relay, whereby said relay on closing immediately re-opens to restore the circuit to a condition permitting repetition of a timing cycle.
2. In an interval timing circuit a current source comprising means adapted to be supplied with alternating current and to rectify the same; a grid-glow tube having main electrodes and a grid; a charging circuit for said grid including a resistor and a grid charging capacitor, said capacitor being connected on one side to one of the main electrodes of said tube and to one side of said current source and connected on its other side through said resistor to the other side of said current source to said current source and to said grid for charging the same to a striking potential at a pre-determined interval after activation of said current source; and a relay connected through said main electrodes of said grid-glow tube to a source of actuating current, said relay including contacts interposed in the connections joining said relay with said actuating current source to interrupt the supply of actuating current for said relay and including contacts connected in discharging relationship to said capacitor to discharge said grid charging capacitor upon excitation of said relay, whereby said relay on closing immediately re-opens to restore the circuit to a condition permitting repetition of a timing cycle.
3. In an interval timing circuit a current source adapted to be controllably activated; a grid-glow tube having main electrodes and a grid; a resistor; a grid charging capacitor connected to one side of said current source through said resistor and to said grid for charging the same to a striking potential at a pre-determined interval after activation of said current source; a connection joining the other side of said current source to one of the main electrodes of said tube; a relay having an actuating coil connected through said main electrodes of said grid-glow tube to a source of actuating current, said relay including contacts interposed in the connection joining said relay coil to said actuating current source to interrupt the supply of actuating current for the actuating coil of said relay when said relay is actuated, and contacts connected in shunt relationship to said grid charging capacitor to discharge the same upon excitation of said relay, said contacts acting immediately upon closing of said relay to cause the same to reopen to place the circuit in condition for repetition of

a timing cycle; load contacts operatively connected to said relay to be actuated thereby; and a control circuit responsive to the actuation of said load contacts by said relay adapted to assume successive circuit positions in response to successive timed interval actuations of said relay.

4. In an interval timing circuit a current source adapted to be controllably activated; a grid-glow tube having main electrodes and a grid; interval regulating variable resistor means; a grid charging capacitor connected on one side through said resistor means to one side of said current source and to said grid and on its other side to one of the main electrodes of said tube and to the other side of said current source for charging said grid to a striking potential at predetermined intervals after commencement of charging of said capacitor; a relay having an actuating coil connected through said main electrodes of said grid-glow tube to a source of actuating current, said relay including contacts interposed in the connections joining said coil to said actuating current source to interrupt the supply of actuating current for the actuating coil of said relay upon actuation of said relay, contacts connected in shunt relation to said capacitor to discharge said grid charging capacitor upon excitation of said relay, and load contacts; and a control circuit responsive to the actuation of said load contacts by said relay coil including shiftable means responsive to successive closures of said load contacts cooperatively engaging said time interval regulating variable resistor means to successively vary the same upon successive actuations of said relay whereby the duration of successive timing intervals is altered successively.

5. In an interval timing circuit a current source adapted to be controllably activated; a grid-glow tube having main electrodes and a grid; a relay having a winding, normally open resetting contacts closed when said relay is excited, normally closed resetting contacts opened when said relay is excited, and load contacts; relay circuit connections extending through the main electrodes of said grid-glow tube through said normally closed resetting contacts and through the winding of said relay to said source of current; initial grid control circuit connections connected to one of the main electrodes of said tube and extending through said normally closed resetting contacts of said relay to a first side of said source of current; a capacitor; a timing resistor; intermediate grid control circuit connections joining a first side of said capacitor through said timing resistor to the other side of said current source and joining the other side of said capacitor through said initial grid control circuit connections to the first side of said current source to cause said capacitor to be gradually charged at a rate regulated by said timing resistor when said current source is activated; final grid control circuit connections joining the first side of said capacitor to the grid of said grid-glow tube adapted to apply a striking charge thereto when said capacitor becomes charged to a pre-determined potential; and discharging circuit connections connected through the normally open resetting contacts of the relay to said capacitor in shunt relation thereto for discharging the same when said relay moves to excited position whereby the timing circuit is prepared at the end of one timing function for a succeeding timing function.

6. In an interval timing circuit a source of alternating current adapted to be controllably acti-

vated; a grid-glow tube having main electrodes and a grid; a relay having a winding, normally open resetting contacts closed when said relay is excited, normally closed resetting contacts opened when said relay is excited, and load contacts; relay circuit connections extending through the main electrodes of said grid-glow tube through said normally closed resetting contacts and through the winding of said relay to said source of alternating current; a first capacitor; a rectifier; initial grid control circuit connections joining said first capacitor through said rectifier and said normally closed resetting contacts of said relay to said source of alternating current for charging said first capacitor upon activation of said alternating current source; a second capacitor; a timing resistor; intermediate grid control circuit connections joining a first side of said second capacitor through said timing resistor to a first side of said first capacitor and joining the other side of said second capacitor to the other side of said first capacitor and to one of the main electrodes of said tube to cause said second capacitor to be gradually charged at a rate regulated by said timing resistor when first capacitor becomes charged; final grid control circuit connections joining the first side of said second capacitor to the grid of said grid-glow tube adapted to apply a striking charge thereto when said second capacitor becomes charged to a pre-determined potential; and discharging circuit connections connected through the normally open resetting contacts of the relay in shunt relation to said first and second capacitors for discharging the same when said relay moves to excited position whereby the timing circuit is prepared at the end of one timing function for a succeeding timing function.

7. In an interval timing circuit a source of alternating current adapted to be controllably activated; a grid-glow tube having main electrodes and a grid; a relay having a winding, normally open resetting contacts closed when said relay is excited, normally closed resetting contacts opened when said relay is excited, maintaining contacts and load contacts; relay circuit connections extending through the main electrodes of said grid-glow tube said normally closed resetting contacts and through the winding of said relay to said source of alternating current; a first capacitor; a rectifier; initial grid control circuit connections joining said first capacitor through said rectifier and said normally closed resetting contacts of said relay to said source of alternating current for charging said first capacitor upon activation of said alternating current source; a second capacitor; a timing resistor; intermediate grid control circuit connections joining a first side of said second capacitor through said timing resistor to a first side of said first capacitor and joining the other sides of said capacitors to one another and to one of the main electrodes of said tube to cause said second capacitor to be gradually charged at a rate regulated by said timing resistor when said first capacitor becomes charged; final grid control circuit connections joining the first side of said second capacitor to the grid of said grid-glow tube to apply a striking charge thereto when said second capacitor becomes charged to a pre-determined potential; discharging circuit connections connected through the normally open resetting contacts of the relay to said first and second capacitors in shunt relation thereto for discharging the same when said relay moves to excited position; and a maintaining circuit controlled by said maintain-

ing contacts adapted to maintain excitation of said relay after opening of said normally closed resetting contacts.

8. In an electrical apparatus adapted to assume a plurality of circuit positions and to shift successively at pre-determined intervals subject to independent adjustment, from position to position, the combination comprising a grid controlled tube having main electrodes and a grid; a current source adapted to supply current at a grid charging potential sufficient to render said tube conducting; a capacitor connected to a main electrode of said tube and the grid thereof; a plurality of independently adjustable resistor means each adapted to be selectively connected between said capacitor and said current source to cause charging of said capacitor to a potential at which said tube will become conducting at rates determined by the particular resistor means and the position of adjustment thereof forming the connection between the capacitor and said current source; resistor selecting switching means adapted to be shifted to select the particular resistor means forming the connection between the current source and the capacitor; a relay having an actuating coil connected through the main electrodes of said tube to a source of actuating current to be excited thereby, said relay having a plurality of contacts movable upon excitation of its actuating coil; a first electro-magnetically actuated control switch connected through some of said relay contacts to a control current source

to be actuated thereby upon the first excitation of said relay, said electro-magnetically actuated switch having load contacts and shifting means cooperatively engaging said resistor selecting switching means to alter the selection of said resistor means forming the connection between said capacitor and said current source, and preparatory means operative to prepare a succeeding control switch circuit for actuation by said relay upon the second excitation thereof; and a second electro-magnetically actuated control switch having load contacts connected through said preparatory means and others of said relay contacts to said control current source to be actuated thereby upon a second closing of said relay.
